[57] CLAIM

The ornamental design for a police utility vest, as shown and described.

DESCRIPTION

FIG. 1 is a perspective view of a first embodiment of the police utility vest and illustrating the mesh body design, reinforced collar and pockets and pouches;
FIG. 2 is a front view of the vest of FIG. 1;
FIG. 3 is a rear view of the vest of FIG. 1 and illustrating an attached carry pouch having a single panel;
FIG. 4 is a right side view of the vest of FIG. 1;
FIG. 5 is a left side view of the vest of FIG. 1;
FIG. 6 is a top view of the vest of FIG. 1;
FIG. 7 is a bottom view of the vest of FIG. 1 and illustrating inside portions thereof; and,
FIG. 8 is an alternate rear open view of the vest of FIG. 3 showing partial detachable release of the carrying pouch thereof.
